UNITED STATES PATENT OFFICE

122,150

DESIGN FOR A CONTROL PANEL BOOTH

Howard F. Spencer, Pittsburgh, Pa., assignor to
Amco, Incorporated, Pittsburgh, Pa., a corpora-
tion of Pennsylvania

Application August 19, 1939, Serial No. 86,784

Term of patent 3½ years

To all whom it may concern:

Be it known that I, Howard F. Spencer, a citizen of the United States and resident of Pittsburgh, county of Allegheny, and State of Pennsylvania, have invented a new, original, and ornamental Design for a Control Panel Booth, of which the following is a specification, reference being had to the accompanying drawing, forming part thereof, in which:

Figure 1 is a side perspective view of a control panel booth, showing my new design, and
Figure 2 is a rear perspective view thereof.

I claim:

The ornamental design for a control panel booth, as shown.

HOWARD F. SPENCER.
